CURLER FOR MAKING PIN CURLS

Josephine H. Moses and Edmund Quincy Moses,
Scarborough, N. Y.

Application April 21, 1949, Serial No. 88,838

2 Claims. (Cl. 132—33)

1

This invention relates to hair curlers and particularly to curlers for making that type of curl commonly known as "pin curls" or sometimes as "flat curls" in which a strand of hair is curled into a toroidal form and pinned closely to the surface of the scalp, the axis of the curl being normal to the head surface. Curls of this type are largely used by hairdressers, who acquire considerable skill in curling the hair around the finger. It is well known, however, that when the hair is wound around the finger to form a flat pin curl, the end of the finger is placed against the head and the hair is then wound from the scalp out, thus resulting in the ends of the hair being on the upper rim of the curl, making it necessary to invert the formed curl before it is fastened in order to have the hair ends next to the scalp. This can be done by a professional operator, but is difficult, particularly on the back of the head, when doing one's own hair.

In accordance with the present invention, means are provided which will enable a woman to make thoroughly satisfactory pin curls on any part of her own head. The curler of the present invention includes a mandrel upon which the hair may be wound, starting with the tip and winding the hair towards the scalp so that the tip ends of the hair are on the inside of the curl. This is accomplished by providing clamping means of such character as to hold the tips of the hair in position upon the mandrel while the curl is being started, the clamping means coinciding with the rounded surface of the mandrel in such a way that the hair ends will not be kinked or sharply bent so as to stick out when the curl is combed out. The clamping means are furthermore provided with an opening or slot which greatly facilitates the removal of the curl from the mandrel, it being possible to press the thumb or finger over the hair and between the sides of the slot, thereby sliding the wound hair including the ends of the hair which were under the clamp down to the end of the curler without displacement of such ends from their position within the curl, resulting in the hair ends being still innermost of the curl and against the scalp. The mandrel is also provided with a forked formation at the end in which the space between the fork portions is of the maximum available width with respect to the diameter of the mandrel and is also of substantial depth lengthwise of the mandrel. This formation facilitates the introduction of the bob pin or clip in a fully opened position so that it may easily be manipulated to receive the curl. Also owing to the formation of the

forked part of the mandrel, the position of the opening may be readily determined by the touch of the fingers, thereby enabling the pin or clamp to be readily entered into the opening, even when 5 curls are being made on the back part of the head where the curl is invisible to the operator.

The clamp having the slot for the purpose of permitting disengagement of the wound hair without distorting the curl, is adjacent to the 10 opening in the mandrel and extends beyond the end of said opening. Thus, when the curler is grasped between the fingers with the point of contact of either thumb or finger being between the prongs at the sides of the slot in the clamp, it will be held so that the fork opening in the mandrel is in position to receive a pin or clip diametrically of the curl.

With the foregoing considerations in view, it is the principal object of the present invention 20 to provide a curler for making the character of curl referred to in a simple and effective manner and which the person making the curls may use on any part of her own head to produce a curl having all of the characteristics usually obtainable only by employing the services of a skilled hairdresser.

Another object of the invention is to provide a curler of the character described in which means are provided for holding a bob pin in 30 opened or partly opened condition where it may be readily grasped and manipulated so as to properly grasp or clamp the curl.

Another object of the invention is to provide a curler of the character described which may be 35 constructed and assembled in a very effective but inexpensive manner.

Another object of the invention is to provide a curler in combination with a pin or clip having a formation coacting therewith for holding the 40 formed curl in desirable shape, the construction of the parts being such as to assure the proper positioning of the pin or clip with respect to the formed curl.

Another object of the invention is to provide 45 improved curl securing means for use with a curler of the character described.

Other objects and advantages will appear in the course of the following detailed description of certain preferred embodiments of the invention 50 illustrative of the best modes now known for practicing the same, it being understood, however, that other embodiments of the invention are possible and are intended to be included within the scope of the invention as herein set forth.

In the accompanying drawings:

Figure 1 is a side elevation of a preferred form of curler embodying the invention, part of the curler body being shown in section;

Figure 2 is a plan view of the curler shown in Figure 1;

Figure 3 is a fragmentary longitudinal section on line 3—3 of Figure 2, showing the pivot and spring construction on a larger scale;

Figure 4 is a transverse section on line 4—4 of Figure 1;

Figure 5 is a transverse section on line 5—5 of Figure 1;

Figures 6 and 7 are perspective views illustrating steps in the manipulation of the curler;

Figure 8 is a side elevation of a bob pin of a form particularly suited for use in combination with the curler of the present invention;

Figure 9 is a diagrammatic view, showing a part of the forked end of the curler, showing an improved curl holding clip being manipulated in combination with the curler to engage a pin curl of toroidal form which is shown in section;

Figure 10 is a plan view of the form of clip shown in Figure 9;

Figure 11 is a transverse section of the clip taken on line 11—11 of Figure 10;

Figure 12 is a side elevation of a modified construction of curler parts being broken away;

Figure 13 is a transverse section on lines 13—13 of Figure 12;

Figure 14 is a transverse section on line 14—14 of Figure 12;

Figure 15 is a view partly in side elevation and partly in longitudinal section of another modified form of the curler;

Figure 16 is a transverse section on line 16—16 of Figure 15; and

Figure 17 is a transverse section on line 17—17 of Figure 15.

Referring to the drawings in detail, the curler shown in Figure 1 comprises a mandrel or barrel 20 which may be either solid or partly or wholly hollow, it being conveniently formed as a tube with a bore 22 extending entirely through the same. Pivotally mounted upon the mandrel is a clamp 24 for engaging with the tips of the hair to start the curl and enable it to be wound upon the mandrel from the inside outwardly as the strand of hair is wound up by rotation of the mandrel towards the scalp. The tips of the hair are engaged under the clamp while the remaining convolutions of the curl are wound over the clamp as well as the mandrel.

The clamp may be mounted upon the mandrel in any suitable manner. A very desirable construction from the point of view of manufacture and one which facilitates the assembly of the clamp upon the mandrel in the most inexpensive manner is shown in Figures 1—4. As here illustrated, the mandrel has ears 26 formed thereon which are provided with slots 28 opening in an axial direction into enlarged bearing recesses 30. Such a mandrel may be formed most inexpensively by molding it from a plastic such, for example, as polystyrene. By utilizing a two-part mold having a parting plane corresponding approximately with the dotted line a—b shown in Figure 1, the mandrel can be formed as a unit with the ears 26 thereon and slots and recesses 28 and 30 may be molded at the same time by use of core pieces carried by the left hand mold section. The portions of the mandrel at opposite sides on the parting plane are preferably tapered longitudinally very slightly towards their ends which will facilitate removal

from the mold sections. It will be observed that the slots 28 are narrowed slightly so that the width of the passage through them is slightly less than the diameter of the recesses 30. This

will not prevent proper removal of the core pieces, however, as the plastic will yield sufficiently to permit that to be done. This same characteristic of the plastic ears with the slots and recesses also permits the assembly therewith of the pivot pin 32 upon which the clamp itself is pivoted. The clamp in the form shown has a body portion 34 provided with downwardly turned flanges 36 which loosely enclose the ears 26 and which carry the pivot pin 32. Suitable spring means are provided, such for instance as the coiled torsion type spring 38, the coiled part of which surrounds the pivot pin 32 and which is provided with projecting legs 40 and 42 which engage, respectively, the underside of the clamp body 34, and the surface of the mandrel between the ears 26. This construction makes for very easy assembly as the spring may be threaded on the pivot pin and the latter riveted over so as to secure the same permanently between the ears 26 of the clamp before any of these metal parts are attached to the mandrel. The leg 42 of the spring will project at an angle from the clamp before assembly as indicated, for example, by the dotted lines 42a in Figure 3. In assembling the metal parts with the plastic mandrel, the clamp and spring are manipulated in such a way that the leg 42 of the spring is bent from the dotted position 42a to the full line position 42 as the clamp and spring assembly is moved longitudinally of and towards the axis of the mandrel as the clamp and pivot pin 32 are brought into a position where the pivot pin may be snapped through the slots 28 and firmly seated in the recesses 30. This simple operation firmly attaches the clamp to the mandrel and at the same time tensions the spring so that it will bias the clamp in a direction to hold the clamping part of the same in firm engagement with the mandrel until it is lifted out of such contact by the manipulation of the finger piece 44 at the end of the clamp body.

The clamping part of the clamp is preferably formed with a pair of prongs 46 which may conveniently be provided with stiffening ribs 48 and which enclose between them an elongated opening or slot 50. This slot extends as far as convenient towards the clamp pivot and should be of such length as to overlie that part of the mandrel about which the curl is to be formed. The slot should be as wide as it can conveniently be made, dependent upon the size of the mandrel. It may be of the same width throughout, but as shown it is wider at its end nearest to the pivot than it is at the tip of the clamp. It is desirable for the slot 50 to extend all the way to such tip, although as stated, the outer part of the slot may be of reduced width. The tip 52 of the clamp should terminate a substantial distance from the end of the mandrel so that the ends of the curl may be completely withdrawn from under the clamp before the mandrel is removed from it.

In the end of the mandrel which the clamp overlies, a trans-axial opening 54 is formed which divides the end of the mandrel into a pair of spaced fork members 56. If the mandrel has a central bore of such diameter that it is as large or larger than the width of the trans-axial opening, then the opening 54 is in fact formed by cutting two aligned areas through the walls of

the mandrel as is apparent from Figure 5. The trans-axial opening should be of as great a width as can be readily formed in the mandrel without weakening the fork portions beyond a safe strength and without having the effect of decreasing their width to a point where they do not provide sufficiently broad curved surface portions 58 to properly support the curl and hold it in the desired form. In practice, the opening, to accomplish these results, may be made of a width equal to or slightly exceeding half the diameter of the mandrel. By way of example, the mandrel may be made of a diameter of approximately $\frac{1}{2}$ " and the trans-axial opening may have a diameter of $\frac{1}{4}$ " to $\frac{5}{8}$ ". These dimensions are merely illustrative, but a mandrel diameter of about $\frac{1}{2}$ " produces a curl of a size usually found desirable. To meet these conditions where a smaller curl is desired, as near the temple or nape of the neck, a smaller model of the curler may be provided. The longitudinal depth of the opening from the tips 60 of the forked portions to the end or bottom 62 of the opening should be sufficient to permit a fully opened bob pin or curl clip to be inserted with one leg of the pin or clip close to the scalp and the other leg embracing the top of the curl. In order to surely permit this result to be accomplished, the depth of the opening should usually be at least twice the diameter of the mandrel. The edges of the forked portions at the sides of the opening should preferably be well rounded off, as indicated at 64 in Figure 5. This enables such rounded edges to be used as effective finger guides for enabling the user to locate the opening by feeling so as to determine its position and enable her to properly place the bob pin or clip even though the curl may be on the back of the head where it cannot be seen. The location of the opening by touch is further facilitated by the fact that if it is made of a width approximating at least half of the diameter of the mandrel, the curved edge portions 64 of the forked portions 56 will be offset inwardly of the main diameter of the mandrel, as clearly shown in Figure 2. The tips 60 of the forked portions should be well rounded off, as indicated, so as to enable the end of the mandrel to be pressed against the scalp without discomfort.

The mandrel is preferably made out of a smooth hard surfaced plastic, polystyrene being one plastic very suitable for the purpose, although any other plastic having similar physical characteristics may be utilized. As such plastic gives a very smooth and finished surface, the curl may be slid off from the mandrel with great facility. The mandrel may also be slightly tapered from its center towards its ends and such very slight tapering of the part of the mandrel upon which a curl is formed will further facilitate the removal of the curl.

The use of the curler will be clear from what has been said. A strand of hair of proper size and preferably not too bulky is combed out and its end laid on the mandrel under the clamp 24 which has been raised by depressing the finger piece 44. The ears 26 projecting from the mandrel form effective stop means for preventing the hair from being wound too far up on the mandrel. When the tips of the hair are properly secured under the fingers 46 of the clamp, the curler is rotated in a direction to wind the strand of hair smoothly upon the mandrel from the tips towards the scalp. When this winding operation has been carried as close to the scalp as is de-

sired, the user swings the mandrel through approximately ninety degrees, so that it is held in a position generally normal to the head surface, as shown in Figure 6. The user then grasps the mandrel between the thumb and fingers with one finger, usually the thumb, placed over the slot or opening 50 at the top of the curl where it will engage with the tips of the hair clamped under the clamp; the fingers are then manipulated so as to push the curl towards the scalp, thus flattening it out, sliding it off the clamp and forcing the tips of the curl from under the clamp, so that the curl is held by the fingers in flattened condition close to the surface of the scalp, the curl still being supported, however, upon the rounded outer surface 58 of the forked ends 56 of the mandrel beyond the tip 52 of the clamp. As the thumb or finger sliding along the slot in the clamp can be relied upon to push the hair tips from under the clamp, it is unnecessary to open or attempt to open the clamp at this time by pressure upon the finger piece 44. Such action is inconvenient and furthermore the clamp cannot be lifted without loosening the curl as all of the convolutions of the curl except the first one are wound over the clamp itself. As the curler is small and light, particularly where it is made of a hollow plastic formation, as shown in Figure 1, it may be readily held in position normal to the scalp between the fingers of the hand holding the curl close to the scalp. The user then takes a bob pin or curl clip in the other hand, opens it wide, and passes one leg of the pin or clip under the curl close to the scalp and the other leg through the opening 54 over the curl. As the curl still surrounds the end of the mandrel and as the opening 54 passes diametrically across the mandrel, it is impossible for the user to apply the bob pin or clip in any but a position diametrically across the center of the curl, thus assuring that the curl will be properly and symmetrically gripped. Owing to the slot 50 in the curler clamp and to the formation of the edges 64 at the sides of the opening 54, the location of the opening 54 may be readily determined by feeling, in instances where visual observation is impossible. Thus, accurately formed curls can be made at the back of the head, as well as at the sides or front.

Figure 7 shows a bob pin being inserted through the trans-axial opening in the curler so as to grip the curl before complete removal from the mandrel. Figure 7 also shows completed curls on the head of the user adjacent to the curl to which the pin is being applied. While any form of bob pin or curl clip may be utilized, provided the latter is not too wide to go through the opening, it is desirable to use a form of bob pin or clip which is provided in its upper leg with recessed portions, between which is a projecting portion of a length approximately equal to the diameter of the mandrel and which will enter the central opening of the curl torus. In this way, the curl is held in the proper toroidal form without subjecting the thicker portions of the curl to excessive clamping pressure during drying.

Figure 8 shows a bob pin of this form in which the lower leg 70 which is inserted next to the scalp is straight or approximately so, while the upper leg comprises a pair of outward curved portions 72 separated by a relatively straight portion 74 which will lie in more or less close contact with the leg 70 while the curl itself is held clamped under the curved portions 72.

The rear or outer end of the mandrel which is preferably hollow, as described, is desirably provided with a beveled end 68. This permits a bob pin which may be of any ordinary type or may be of the particular form shown in Figure 8, to be inserted over the beveled end 68 with one leg inside of the bore of the mandrel and the other leg on the outside, as shown in Figure 1. If a bob pin is put on the mandrel in this manner before each curl is made, it will be readily found by the fingers of the user at the instant when it is desired to insert the same in a position to grasp the curl, as shown in Figures 6 and 7. The bob pin will furthermore be held in open or partly open position by the mandrel wall so that it may be readily manipulated into fully open position by the fingers prior to its application to the curl. The use of the wall of the mandrel at the rear end of the curler for temporarily holding the bob pin is, of course, purely optional with the user.

Figures 9, 10 and 11 show a form of clip particularly adapted for use in combination with the curler for the holding of the formed pin curl. In the construction shown in these figures, the curl clip comprises an inner plate or leg 78 which may be straight or nearly so, so as to lie close to the surface of the scalp, and another leg or plate 80 is assembled in pivotal relationship to the plate 78, which is preferably formed with outwardly curved portions 82 separated by a straight depressed portion 84 of a length approximating the diameter of the mandrel or width of the forked portion thereof so as to enter the open center of the curl which is clamped under the curved portions 82, as shown in Figure 9. The clamp members 78 and 80 may be secured together in any suitable manner, permitting their pivotal opening. As illustrated, they are shown as held together by a short elastic band 86 of rubber or plastic which encloses and is held in position by enlargements 88 on the clamp members. The rear ends of the clamp members are spaced and properly shaped to form finger grips 90 and 92, by which the clamp members may be separated. The clamp members may be made of metal, if desired, but are preferably formed of a suitable plastic. In the latter event, they may be ribbed or transversely curved, as shown in Figure 11, so as to increase their resistance to bending. They thus may be made of ample stiffness while of such width that they may be readily passed through the opening 54. Obviously, any other way of pivotally connecting the clamp members may be employed in place of the elastic band construction shown.

A modified construction of curler is shown in Figures 12, 13 and 14. In this construction, a plastic mandrel is utilized which may be either hollow or may be solid, as shown in these figures, and upon which no projecting ears are molded. In place of using projecting ears, a metal band 124 is clamped about the mandrel in any suitable manner, as for example by means of a tubular rivet 126. If desired, the band 124 may be fitted into a groove 128 in the mandrel, although this is not necessary unless it is desired to secure a perfectly flush finish between the surface of the band and the surface of the mandrel. The band 124 has outwardly projecting ears 130 through which the tubular rivet 126 passes, the clamp 24, which may be of the same form as the clamp shown in Figures 1 to 6, being secured to the ears 130 by means of a pivot pin 32 passing through the tubular rivet 126. A spring 138 is shown as mounted upon the tubular rivet. If the mandrel is of solid construction, as illustrated, it may be

tapered at its outer end as shown at 140 and may be provided with a central hole 142 of such size as to receive one leg of a bob pin. The other end of the mandrel is provided with an opening 54, as already described in connection with previous figures.

A mandrel of elliptical section has been shown in Figures 12, 13 and 14, instead of a mandrel of circular cross-section, as shown in Figures 1, 10, 2, 3 and 5. The elliptical section will produce a curl which in practice is not distinguishable in appearance from a circular curl. The elliptical form, however, has the advantage of giving greater width in the direction of the major axis of the ellipse, thereby permitting the making of the trans-axial opening 54 wider with respect to the circumferential dimension of the curl than is possible with a circular mandrel. By making the opening 54 wider, it is possible to introduce 15 a wide clip for gripping the curl, such wide clips being frequently used at the present time for the clamping of pin curls.

Another modified construction of curler is shown in Figures 15, 16 and 17. The construction of curler here illustrated lends itself to manufacture entirely out of plastic, except as to the spring. The curler body or mandrel 140 is generally similar in shape to the mandrels described and is provided at one end with a trans-axial opening 54. It is shown as having a molded recess 142 formed therein, such recess having parallel sides 144 and an arcuate bottom surface 146. The clamp is shown as a molded integral body of plastic 148 which has a disc-like body portion 150 fitting in the recess 142 with such closeness as to permit it to rotate freely between the walls of the recess. A pivot 152 which may be made of plastic, if desired, passes through holes in the mandrel concentric with the curved wall 146 of the recess, such pivot also passing through a hole in the clamp body 150. The clamp body 150 carries a pair of clamping arms 154 between which is a space 156 serving the same purpose as the slot or space 50 in the form of clamp shown in Fig. 2. The clamp body also carries an operating finger piece 158 which is preferably of the same width as the body and can be depressed into an extension 160 of the recess 142. The lower portion 162 of the finger piece 158 preferably extends into the recess portion 160 when the clamp is completely closed, so that no part of the interior of the recess 142 or of its extension 160 is visible in a completed curler. Thus, a smooth, attractive 45 appearance is secured and dirt is also excluded from the recess. Any suitable type of spring may be used for biasing the clamp into closed position. As shown, a coil spring 164 is used which is mounted in a portion of the recess.

From the foregoing it will be seen that a curler for making pin curls has been provided which is very effective in use and simple to manufacture, and which involves no complications such as ejectors or pushers for attempting to remove the curl or apply the bob pin or clamp or other curl holding means to the curl. Such complicated devices not only require extra manipulation on the part of the user of a character which the user cannot perform without special instruction or practice, but may result in danger of the hair becoming caught in the ejector means or other special devices. The curler of the present invention can be manipulated by the fingers in a natural manner and provides an exceedingly

simple and effectual aid facilitating the natural manual operations of making a curl.

While certain preferred embodiments of the invention have been illustrated and described in detail, it is to be understood that changes may be made therein and the invention embodied in other structures. It is not, therefore, the intention to limit the patent to the specific constructions illustrated, but to cover the invention broadly in whatever form its principle may be utilized.

We claim:

1. A pin curler comprising a mandrel of unitary construction the outer end constituting a hand grip portion, and having a wide deep opening extending transversely through the same from the inner end of the mandrel for a substantial distance longitudinally thereof so as to form the end of the mandrel into a pair of spaced fork portions, said fork portions having smooth curved outer surfaces upon which the hair may be curled and from which the curl may be easily slid off longitudinally, said fork portions having smooth rounded edges extending longitudinally of said transverse opening to guide the fingers of the user and facilitate the introduction of the curl holding pin or clip between said fork portions into position to engage a curl surrounding said fork portions, the opening between said fork portions being unobstructed and being deep enough to permit introduction of the bob pin in an open pin position, and an elongated clamp pivoted to said mandrel at a point further from the forked end of the mandrel than the end of the transverse opening, said clamp being of concave transverse section fitting over the smooth curved surface of one of said fork portions, and means for biasing said clamp so as to normally hold the clamping portion in clamping engagement with the surface of the mandrel at one side of the transverse opening therethrough, the tip of said clamp extending lengthwise of the mandrel beyond the end of said transverse opening but terminating a substantial distance short of the end of the mandrel.

2. A pin curler comprising a mandrel of light unitary construction, the outer end constituting

a hand grip portion, and having a wide deep opening extending transversely through the same from the inner end of the mandrel for a substantial distance longitudinally thereof so as to form the inner end of the mandrel into a pair of spaced fork portions, said fork portions having smooth outer surfaces upon which the hair may be curled and from which the curl may be easily slid off longitudinally, said fork portions having smooth rounded edges extending longitudinally of said transverse opening to guide the fingers of the user and facilitate the introduction of the curl holding pin or clip between said fork portions into position to engage a curl surrounding said fork portions, and an elongated clamp pivoted to said mandrel at a point further from the forked end of the mandrel than the end of the transverse opening, said clamp having a clamping section fitting over the smooth surface of one of said fork portions.
